UNITED STATES PATENT OFFICE

113,671

DESIGN FOR A GAME BOARD

Harry S. Jones, South Orange, and Robert P. Moore, Livingston, N. J.

Application July 6, 1938, Serial No. 78,309

Term of patent 3½ years

To all whom it may concern:

Be it known that we, Harry S. Jones and Robert P. Moore, citizens of the United States and residents, respectively, of South Orange and Livingston, in the county of Essex and State of New Jersey, have invented a new, original, and ornamental Design for a Game Board, of which the following is a specification, reference being had to the accompanying drawing, forming part thereof.

We claim:

The ornamental design for a game board, as shown.

HARRY S. JONES.
ROBERT P. MOORE.
